WESTON M. FULTON, OF KNOXVILLE, TENNESSEE, ASSIGNOR TO THE FULTON COMPANY, OF KNOXVILLE, TENNESSEE, A CORPORATION OF MAINE.

STEAM-BOILER ATTACHMENT.

1,097,124.

Specification of Letters Patent.

Patented May 19, 1914.

Original application filed November 18, 1912, Serial No. 732,059. Divided and this application filed October 27, 1913. Serial No. 797,666.

To all whom it may concern:

Be it known that I, WESTON M. FULTON, a citizen of the United States of America, and resident of Knoxville, Tennessee, have 5 invented a new and useful Improvement in Steam-Boiler Attachments, which invention is fully set forth in the following specification.

This invention relates to improvements 10 in steam boiler attachments, and particularly to devices of this class which are adapted to indicate and control steam pressure and regulate the air draft in house heating furnaces.

15 It is customary to provide a house heating steam furnace with a steam gage, a damper regulator and some form of safety valve such as a pop-off valve. Each of these devices necessitates tapping separate 20 openings into the boiler casting. This practice requires three separate handlings of a heavy and bulky casting on the drilling machine as this operation is usually done at the factory. The manipulation of 25 this bulky casting requires the expenditure of labor and time and the casting is unnecessarily weakened at these points unless special provision is made in making the casting to strengthen the areas into which 30 the holes are drilled. Furthermore, the chances of leaking at the places where these connections are made increases with the number of openings and this is particularly the case if the openings are made at the 35 place where the furnace is installed since the facilities of the factory are absent at such times.

It is the object of this invention to overcome the above objections as far as practicable by providing a unitary structure 40 which is adapted to carry a plurality of fluid pressure devices and requires but one tapping of the boiler for making the connection therewith.

45 A further object is to improve the means of attaching a vibratory vessel to its base after the vessel has received its end closures, and by clamping means inside the vessel, such means being particularly useful 50 in connection with my unitary support.

In order that the invention may be readily understood, reference is had to the accompanying drawing which shows a chambered base 40 of cast metal, supporting a

steam gage 46, a vibratory damper operating vessel 41, and a pop-off valve 48. The base 40 is provided with a threaded fitting 44 adapted to be secured to a steam boiler, not shown.

42 and 43 are branch passages in the base 60 which connect the steam gage 46 and pop-off valve 48 with the central space in the casting.

The valve and gage may be secured in position in any suitable manner. As illustrated, the gage is provided with a nut 47 which receives a nipple 45 adapted to be screwed into the threaded opening at the end of the branch passage 43. The top of the casting 40 is formed with a seat for receiving a vibratory vessel 41, and is provided with a threaded opening, with which registers an opening in the lower end wall of the vessel 41 for receiving a flanged clamping nut 54 having an interior lug 55. 70 This nut is placed inside the vessel before the latter finally receives its second end-closure, and is screwed into the threaded opening in the base 40 by aid of a spud or wrench inserted through the opening in the 75 fitting 44 and engaging lug 55. The flange of the nut thus clamps the end wall steam-tight against the base 40. The base 40 also supports a bracket arm 49 held in place by a long bolt 51 and nut 52. This bracket 49 80 carries a rocker 50 operated by a power member 53 secured to the movable end wall of the vibratory vessel 41. A damper lever 22 is secured to the rocker and has connections with a furnace damper, not shown. 85

The operation of the device will be readily understood from the drawing and description and needs no further explanation.

This application is a division of my earlier application Serial No. 732,059, filed 95 November 18, 1912.

What is claimed is:—

1. In a steam boiler attachment, the combination of a rigid support having a steam supply inlet, a vibratory vessel having non-flexible end walls, one of said walls being in open communication with the steam supply inlet and being secured thereto by means of a flanged bushing having the flange on the interior of the vibratory vessel and being provided with means whereby said bushing may be secured to place by the application of power exterior to the vessel. 100 105

2. In a steam boiler attachment, the combination of a corrugated collapsible and expansible vessel, one end of which is movable and is provided with an inelastic end closure, the opposite end of said vessel being stationary and having a closure provided with an opening, a support having a threaded opening registering with that of said end closure, and a flanged screw-threaded bushing provided with an internal lug, said bushing being adapted to be screwed into said opening while inside of said vessel to secure said parts together.
3. In a steam boiler attachment for supporting a plurality of fluid pressure devices and connecting the same with the

steam space of the boiler through a single tapping of the boiler wall, a hollow casting having a threaded connection for attachment with the boiler, a seat for receiving a vibratory vessel, a vessel on said seat and in open communication with the space in the casting, and one or more connections for receiving fluid pressure devices also in open communication with said space. 25

In testimony whereof, I have signed this specification in the presence of two subscribing witnesses.

WESTON M. FULTON.
